WINDOW GLASS GUIDE

David C. Bailey, Amesbury, Mass.

Application July 30, 1935, Serial No. 33,851

15 Claims. (Cl. 296—44.5)

This invention relates to that type of window glass guides, which are usually employed in automobile bodies, which are so constructed that they may be readily bent by hand to conform to curved window frames.

5 While guides of this character which have been produced are sufficiently satisfactory in many respects, there is a constant demand for reduced cost of production, and as the cost of materials generally considerably exceeds the cost of labor, a substantial saving in the cost of materials, even though it may result in some increase in the labor cost, is often desirable.

10 The primary object of my invention is to produce a guide of the above described character in the production of which a substantial saving in the cost of materials may be made without increasing the cost of the labor item to an objectionable extent, and which will otherwise be as satisfactory as guides of this character which have previously been produced.

15 I accomplish this object primarily by providing a core, on which suitable cushioning material may be mounted, and which primarily consists of a strip of sheet metal, the middle portion of which has been cut so as to separate the strip into two sections each of which comprises a continuous portion forming an edge of the core and a series of tongues, extending from said continuous portion, the end portions of said tongues being lapped to form the bottom of the core.

20 For a more complete disclosure of my invention, including several forms thereof, reference is made to the following specification in connection with the accompanying drawing in which:

25 Fig. 1 is a view in side elevation showing an embodiment of my invention installed in a window casing.

30 Fig. 2 is a combined perspective and sectional view on an enlarged scale, of a guide embodying one form of my invention.

35 Fig. 3 is a sectional view at line 3—3 of Fig. 2.

40 Figs. 4, 5 and 6 are detail views showing different steps in the formation of the core in the form of channel shown in Fig. 2.

45 Figs. 7 and 8 are detail views showing preliminary operations on the cushioning devices therefor.

50 Fig. 9 is a sectional view showing a modification of the channel shown in Fig. 2.

55 Fig. 10 is a combined sectional and perspective view showing another embodiment of my invention.

Figs. 11 and 12 are detail views showing steps in the formation of the core employed in the form of channel shown in Fig. 10.

The form of my invention shown in Fig. 2 may be best described by an explanation, in a general way, of the manner in which it is constructed.

60 A strip of thin sheet metal, having parallel edges,

is cut or punched in a zig-zag line along the middle thereof, as shown in Fig. 4, dividing the strip into two sections, which comprise continuous edge portions 14, 15, from which a series of equally spaced tongues 16, 17, extend in perpendicular relation, said tongues being, in this instance, straight and having square ends. Said sections are then partly separated laterally, so that the tongues of each section still lie edge to edge in the same alternate positions, with their end portions lapped, as shown in Fig. 5. Each edge portion is then wrapped about a reinforcing wire 18 and 19, and the end portions 16', 17' of the tongues are bent reversely to an extent, also as shown in Fig. 5.

10 A strip 20 of cushioning material such as felt, or a textile material having a heavy nap, is provided, of a width corresponding to the width of the bottom of the channel to be formed, the edge portions of the strip having slits 21 formed at 20 intervals therein, as shown in Fig. 8.

15 Said strip 20 is then placed on the portions of the tongues which lap each other and the end portions 16', 17' of the tongues are then bent about the edge portions of the strip, so that the strip is firmly clamped thereby at each edge, as shown in Figs. 2 and 3, thereby securely connecting said cushioning strip to the core sections, and, as the strip has substantial stability, relative movement of the sections will be prevented.

20 In the present instance metallic finished edges or ornamental beads for the edges of the channel are not desired, and a cushioning side and edge covering of felt, or textile material with a heavy nap, is provided. A strip of the material

25 employed for this purpose is separated into two sections by a zig-zag cut similar to that employed in forming the core sections, said cushioning sections thereby comprising continuous edge portions 22, 23 from which tongues 24, 25 extend. The edge portions 22, 23 are wrapped about the wire reinforced edges of the core sections, so that they extend onto what is to be the inner side of the channel to a sufficient extent to provide a suitable cushion for the sides

30 of the glass, and then about the opposite side across the middle portion, so that the tongues 24, 25 lie against the tongues 16, 17 respectively of the core and extend thereon to the reversely bent end portions 16', 17' thereof. The edge portions 22, 23 of said cushioning sections which are wrapped about the edges of the core may be secured by any suitable means, as by stitches 26

35 which pass through the spaces between the tongues adjacent the edge portions and the remaining portions of said cushioning sections may be secured to the tongues of the core sections by a suitable cement.

40 The parts as thus arranged are then bent into channel form, the reversely bent ends of the

tongues which are clamped to the bottom cushion 20 being located at the vertex of the angle between the bottom and each side, as shown in Fig. 2.

5 The slits 21 in the bottom cushion 20 are spaced apart to correspond to the distance between the tongues 16, 17, and, when the cushion is placed in position, care is taken so to locate the strip that the slits 21 therein at each side are approximately mid-way between the tongues which extend from the section at the side of the channel next the edge, as shown in Fig. 3, so that the slits are located mid-way between the portions which are grasped by the tongues extending 10 from the opposite core section. Consequently, when the channel is bent to conform to a curved window frame, as shown in Fig. 1, the tongues 16, 17 will be swung away from each other to a slight extent, and, as the tongues grasp the 15 strip at their ends, the slits will be slightly opened by this movement of the tongues. This bending movement also tends to stretch the bottom strip, and the slits 21 therein assist in permitting this stretching action, which, for any particular portion, is slight. Also each section of covering material on the outer side of the channel only extends over the tongues of the section to which it is directly attached, so that this material does 20 not obstruct the bending operation, and as the continuous portions of the channel are at the 25 edges of the sides and are very narrow, they may be readily bent and do not interfere with the bending operation to an appreciable extent.

30 The bending operation may therefore be readily performed.

As in use the channel is fitted into a groove of the window casing, there is no possibility that the sections of the channel will become relatively displaced after it is inserted, and the bottom strip 40 20 has sufficient stability to hold the sections in place up to the time of insertion.

It will be noted that a substantial saving of metal for the core is thus made, as the width of the strip, of which it is formed, is substantially less than the sum of the widths of the two 45 sides and bottom of the channel.

When an external covering of thin textile material is employed, the construction is slightly modified, as shown in Fig. 9. In this instance each tongue is bent to provide an intermediate curved portion as 16^a, which registers with the reversely curved portion of the adjacent tongues, so that the bottom of the channel at its corners is not indented. In this form a textile covering 50 21 is extended entirely about the outer sides and bottom of the channel and is clamped by the edges of the core sections, and cushioning strips 28 are arranged on the sides for engagement with the glass, and are secured in like manner. The bottom cushion 29 is clamped by the ends 55 of the tongues as previously described.

Another form of my invention is shown in Fig. 10, in the production of which the strip from which the metal core sections are formed are cut in oblique directions to the edge portions, as 60 shown in Fig. 11, forming two sections having continuous edge portions 30, 31, from which tongues 32, 33 extend in parallel relation, but at an oblique angle to the edges. The edge portions are then reinforced with wires 34, as in the previously described construction, and the sections are completely separated and their positions are reversed relatively, and then they are placed together, as shown in Fig. 12, so that the 65 70 tongues overlap each other alternately, one

tongue of one section being passed over two tongues of the other section, and the next tongue of the first section being passed beneath the two succeeding tongues of the other section, and so on. The sections as thus arranged are then covered with rubber 35 on both sides, preferably by an extruding process, and then they are bent into channel form. 5

In this instance a cushioning strip 36 is cemented to the bottom of the channel and side 10 cushioning strips 37 are secured on the inner sides by cement and by metal edge beads 38, these parts usually being applied before the core is bent into channel form.

When the channel, as thus constructed, is 15 bent to conform to a window frame, the rubber coating between the tongues will yield sufficiently to permit the tongues to be swung apart to the slight extent necessary and the bottom cushion will be stretched sufficiently to permit this action and may be slit, as illustrated in Fig. 8, to facilitate this action.

In this form of my invention a substantial saving in metal of which the core is formed will be made in like manner to that already described 25 with relation to the other constructions and, as the tongues are interwoven, a core is formed which will be sufficiently substantial for the purpose.

I claim:

1. A window glass channel having a channel shaped, sheet metal core composed of two separate sections, each having a side and a bottom portion, the side portion of each section having a continuous edge portion forming an edge of the channel and each section having a series of tongues extending from its edge portions in spaced apart relation, the end portions of the tongues of each section extending over the bottom portion of the channel oppositely to the 40 tongues of the other section and the tongues of each section extending over portions of the spaces between the tongues of the other section. 35

2. A window glass channel having a channel shaped, sheet metal core composed of two separate sections, each having a side and a bottom portion, the side portion of each section having a continuous edge portion forming an edge of the channel and each section having a series of tongues extending from its edge portions in spaced apart relation, the end portions of the tongues of each section extending over the bottom portion of the channel oppositely to the 45 tongues of the other section and the tongues of each section extending over portions of the spaces between the tongues of the other section, each tongue terminating adjacent the opposite side of the channel from the side from which it extends. 50

3. A window glass channel having a sheet 60 metal core composed of two separate sections, each having a continuous edge portion forming an edge of the channel, and a series of tongues extending therefrom, the tongues of each section extending oppositely to the tongues of the other section across the bottom of the channel in lapped relation, and a cushioning strip on said lapped portions of said tongues, each edge portion of which is held in clamping engagement by the adjacent end portions of the tongues. 65 70

4. A window glass channel having a sheet metal core composed of two separate sections, each having a continuous edge portion forming an edge of the channel, and a series of tongues extending therefrom, the tongues of each sec- 75

tion extending oppositely to the tongues of the other section across the bottom of the channel in alternate relation with their edges in close proximity, to form the bottom of the channel, 5 and each terminating adjacent the opposite side of the channel from the side from which it extends, and a cushioning strip on the bottom of the channel, the end portions of said tongues being bent reversely and held in clamping engagement with the edge portions of said strip.

5. A window glass channel having a sheet metal core composed of two separate sections, each having a continuous edge portion forming an edge of the channel and a series of tongues 15 extending oppositely therefrom transversely of the sides and bottom of the channel, the portions of said tongues forming the bottom thereof being arranged edge to edge and each terminating adjacent the opposite side of the channel 20 from the side from which it extends, so that the tongues lie in lapped relation, and a bottom cushion attached to the lapped portions of said tongues.

6. A window glass channel having a sheet metal core composed of two separate sections, each having a continuous edge portion forming an edge of the channel and a series of tongues extending oppositely therefrom transversely of the sides and bottoms of the channel and in 25 perpendicular relation to said sides, said tongues being terminated adjacent the opposite side from the side from which they extend, and a bottom cushion on said tongues the edge portions of which are held in clamping engagement by the 30 end portions of the tongues.

7. A window glass channel having a sheet metal core composed of two separate sections, each having a continuous edge portion forming an edge of the channel, and a series of tongues 40 extending therefrom, the tongues of each section extending oppositely to the tongues of the other section across the bottom of the channel in lapped relation, and a cushioning strip on said lapped portions of said tongues, each edge portion of which is held in clamping engagement by the adjacent end portions of the tongues, said strip having slits in its edge portions to permit bending of the channel.

8. A window glass channel having a sheet metal core composed of two separate sections, each having a continuous edge portion forming an edge of the channel, and a series of tongues extending therefrom, the tongues of each section extending oppositely to the tongues of the other 55 section across the bottom of the channel in lapped relation, and a cushioning strip on said lapped portions of said tongues, each edge portion of which is held in clamping engagement by the adjacent end portions of the tongues, said 60 strip having slits in each edge portion between the tongues which are engaged therewith.

9. A window glass channel having a sheet metal core composed of two separate sections, each having a continuous edge portion forming 65 an edge of the channel, and a series of tongues extending therefrom, the tongues of each section extending oppositely to the tongues of the other section across the bottom of the channel in lapped relation, a cushioning strip secured on said 70 lapped portions of said tongues, and a separate cushioning covering on each edge and side of

said channel having a continuous portion for the edge, and tongue portions for the tongues of the corresponding core section.

10. A window glass channel having a sheet metal core composed of two separate sections, 5 each having a continuous edge portion forming an edge of the channel and a series of tongues extending obliquely from the edge portion of each section, the tongues of each section extending obliquely across the tongues of the other section to form the bottom of the core.

11. A window glass channel having a sheet metal core composed of two separate sections, each having a continuous edge portion forming an edge of the channel and a series of tongues 15 extending obliquely from the edge portion of each section, the tongues of each section extending obliquely across the tongues of the other section in interwoven relation, to form the bottom 20 of the core.

12. A window glass channel having a sheet metal core composed of two separate sections, each having a continuous edge portion forming an edge of the channel and a series of tongues 25 extending obliquely from the edge portion of each section, the tongues of each section extending obliquely across the tongues of the other section, the alternate tongues of one section being disposed at opposite sides of the tongues of the 30 other section.

13. A window glass channel having a channel shaped sheet metal core composed of two separate sections, each having a continuous edge portion forming one edge of the channel and a series 35 of tongues extending therefrom, the tongues of each section forming a portion of the corresponding side of the channel and the end portions thereof extending transversely of the bottom of the channel in lapped relation with the tongues of the other section, and means connected to the tongues of each section to hold 40 said sections against separation.

14. A window glass channel having a channel shaped sheet metal core composed of two separate sections, each having a continuous edge portion 45 forming one edge of the channel and a series of tongues extending therefrom, the tongues of each section forming a portion of the corresponding side of the channel and the end portions thereof extending transversely of the bottom of the channel in lapped relation with the tongues of the other section, and a cushioning strip on 50 said lapped portions of said tongues and connected thereto, to hold said sections against separation and provide cushioning means for the edge 55 of the glass.

15. A window glass channel having a channel shaped sheet metal core composed of two separate sections, each having a continuous edge portion 60 forming one edge of the channel and a series of tongues extending therefrom, in spaced apart relation corresponding in width to the width of the tongues, the tongues of each section forming a portion of the corresponding side of the channel and the end portions thereof extending transversely of the bottom portion of the channel, the tongues of each section being disposed in the spaces between the tongues of the other section.

70 DAVID C. BAILEY.
